CLAIM

The ornamental design for a pistol, as shown and described.

DESCRIPTION

FIG. 1 is a left front perspective view of a first embodiment of a pistol according to the new design;
FIG. 2 is a right front perspective view thereof;
FIG. 3 is a left rear perspective view thereof;
FIG. 4 is a right rear perspective view thereof;
FIG. 5 is a left side elevation view thereof;
FIG. 6 is a right side elevation view thereof;
FIG. 7 is a front elevation view thereof;
FIG. 8 is a rear elevation view thereof;
FIG. 9 is a top plan view thereof;
FIG. 10 is a bottom plan view thereof;
FIG. 11 is a left front perspective view of a second embodiment of a pistol according to the new design;
FIG. 12 is a right front perspective view thereof;
FIG. 13 is a left rear perspective view thereof;
FIG. 14 is a right rear perspective view thereof;
FIG. 15 is a left side elevation view thereof;
FIG. 16 is a right side elevation view thereof;
FIG. 17 is a front elevation view thereof;
FIG. 18 is a rear elevation view thereof;
FIG. 19 is a top plan view thereof; and,
FIG. 20 is a bottom plan view thereof.

All broken lines shown in the drawings are for illustrative purposes only and form no part of the claimed design.
